CONDENSER APPARATUS

Filed Nov. 8, 1918

INVENTOR.
Raymond N. Ehrhart
BY *J. M. Gallister*
his ATTORNEY.

UNITED STATES PATENT OFFICE.

RAYMOND N. EHRHART, OF EDGEWOOD, PENNSYLVANIA, ASSIGNOR TO WESTINGHOUSE ELECTRIC & MANUFACTURING COMPANY, A CORPORATION OF PENNSYLVANIA.

CONDENSER APPARATUS.

Application filed November 8, 1918. Serial No. 261,707.

To all whom it may concern:

Be it known that I, RAYMOND N. EHRHART, a citizen of the United States, and a resident of Edgewood, in the county of Allegheny and State of Pennsylvania, have made a new and useful Invention in Condenser Apparatus, of which the following is a specification.

This invention relates to condenser apparatus and particularly to that class of apparatus used in condensing steam from steam operated power units and the like.

The invention particularly relates to means for controlling the capacity of the air extracting apparatus in response to variations in the amount of air or other non-condensable fluid within the condenser, and is applicable to any type of air pump or ejector serving condenser apparatus.

It is well known in the art that the air or non-condensable fluid content of the fluid entering the condenser varies, making it necessary to extract varying quantities of air from the condenser. Ejectors have been used for this purpose, but ejectors or any other type of air extracting apparatus will be wasteful of steam unless means are employed for varying their capacity in accordance with variations in the amount of air to be handled, since without such means the apparatus must be designed to extract the maximum amount of air encountered and operating conditions and must also continuously operate at full capacity. I have found that by using a plurality of small air extracting devices, such as ejectors having a combined capacity capable of extracting the maximum amount of air encountered under operating conditions, certain of the ejectors may be cut out of service when the quantity of air to be handled is small, resulting in a corresponding reduction in steam consumption.

This invention has for an object to produce an air extracting apparatus, wherein the air extracting capacity thereof is automatically varied to correspond with the amount of air to be extracted.

Another object of the invention is to produce an apparatus wherein the operating fluid supply to the extracting apparatus is varied in accordance with variations in the air content of the fluid within the condenser.

Another object is to produce an apparatus wherein variation in the air content of the fluids within the condenser correspondingly affects apparatus for controlling the steam supply to the ejector apparatus regardless of the quantity or temperature of the steam entering the condenser.

Another object of the invention is to produce a simple, inexpensive apparatus for performing the aforesaid functions.

These and other objects are attained by means of apparatus embodying the features herein described and illustrated in the accompanying drawing wherein—

The figure is a diagrammatic vertical section of apparatus embodying the invention.

Referring to the drawing, the apparatus is shown as applied to a surface condenser 1, although it is applicable to any type of condenser. The apparatus includes a plurality of ejectors 2 connected in parallel with an air off-take conduit 3 leading from the air offtake port 4 of the condenser 1. The ejectors exhaust into an exhaust manifold 5 and the steam admission to each ejector is controlled by a separate valve 6 having an upwardly directed lever 7 adapted to be moved to a valve opening position by a valve rod 8. The valves 6 are preferably of a quick acting type and as diagrammatically illustrated are adapted to be normally held in closed position by means of a spring or other suitable closing means, not shown.

As shown in the figure, the valve rod 8 is in its extreme position toward the right in which all the valves are moved to the fully open position by the stops 9 which may be adjustably secured in such positions along the rod that the levers 7 are successively engaged and the valves successively opened as the rod is moved to the position shown from its normal position.

An object of the invention is to regulate or vary the air extracting capacity of the ejector apparatus so that it corresponds with the air content of the fluid within the condenser. It will be noted that I have employed the word air to include all non-condensable fluids. It is well known that if there is no air within the condenser the vacuum at the region of complete condensation within the condenser will correspond to the temperature of the condensate and

conversely the temperature of the condensate will correspond to the pressure within the condenser. The presence of air within the condenser causes an increase in pressure over that theoretically possible, and consequently the vacuum attained within the condenser will not correspond to the temperature of the condensate and the amount of variation will correspond to the air content of the fluid within the condenser.

In carrying out my invention I provide two receptacles or tanks 10 and 11, the former of which communicates with the condensate offtake passage 12 by means of the conduit 13 and with the hot well of the condenser by means of a pipe 14, so that condensate flows to the tank 10 and rises therein to the level of the condensate in the condenser. The pipe 14 establishes communication between the hot well and the tank at points well above the normal water level.

The tank 11 is similar to the tank 10 and communicates with the lower portion of the tank 10 by means of the pipe 15. The upper portion of the tank 11 communicates with intake of an air extracting device, which is illustrated as a steam actuated ejector. The pipe 18 establishes communication between the upper portion of the tank 11 and the suction chamber 16 of the ejector. Inasmuch as the tank 11 is small and is therefore subject to practically no air leakage, the ejector 17 can easily maintain a theoretical vacuum within the tank, that is, a vacuum corresponding to the temperature of the water in the tank. The vacuum, however, cannot rise appreciably above the theoretical vacuum, because such an increase in vacuum will occasion rapid evaporation of the water which in turn will clog the ejector and reduce its capacity.

From the foregoing it will be apparent that if there is no air within the condenser and the temperature of the condensate in the tanks 10 and 11 is substantially the same as the condensate within the condenser, the pressure within the condenser 1 and the tank 10 will be the same as the pressure within the tank 11, in which the pressure is the lowest attainable, and as the condenser and the tanks are intercommunicating, the condensate in the condenser and the tanks will therefore be at the same level.

As previously stated, air within the condenser increases the pressure within the condenser over the theoretical pressure corresponding to the temperature of the condensate and the increase corresponds to the air content of the fluid within the condenser. For this reason air within the condenser 1 will be indicated by the fact that the level of the condensate within the tank 10 will be depressed below the level of the

condensate within the tank 11, and the difference in level will correspond to the air content of the condenser. This difference in the level of the condensate in the two tanks 10 and 11 is employed in controlling the valves 6 of the different ejectors 2 so that they will open or close in response to variations in air content of the fluids within the condenser.

The tanks 10 and 11 are provided respectively with floats 19 and 20 adapted to be buoyed by the condensate within the tanks and which consequently will rise and fall with the level of the condensate therein. The tanks are designed to provide ample space above the floats, so that they may have ample range vertically to allow for large fluctuations in the quantity and level of the condensate within the condenser. It will be understood that the relative position of the float 20 with respect to the float 19 depends entirely upon the difference in pressure, within the tanks, and the floats of the device function accurately regardless of the level of the condensate within the condenser. If the condensate level in the condenser is high the floats 19 and 20 will be correspondingly high.

The floats 19 and 20 are provided respectively with stems 21 and 22 which project vertically through suitable packing glands 19' and 20' respectively and are pivoted to opposite ends of the rocking beam 23 adapted to oscillate about a central hub 24. The hub 24 is slidably mounted within a vertical slot 25, provided in a guide 26, so that the beam 23 may move vertically when the level of the condensate within both tanks is concurrently and equally altered by reason of an increase or decrease in the quantity of condensate within the condenser.

When the level of the condensate within the tank 11 rises above the level of the condensate in the tank 10, the effect will be to raise the float 20 and swing the beam 23 about the hub 24 as a pivot. The beam is provided with an upwardly projecting arm 27 provided at its free end with a pin 28 adapted to operate in a vertical slot 29 located in a clevis 30 which is mounted on the end of the valve rod 8. As shown, the float 20 is raised above the float 19, indicating a high air content of the fluid in the condenser, and the arm 27 is tilted to the right sufficiently to hold all the valves 6 open so that the extracting capacity of the ejectors is increased to the maximum.

When the combined operation of the ejectors has reduced the air content of the fluid within the condenser, the float 20 will be lowered correspondingly, thereby shifting the position of the valve rod 8 and permitting the valves 6 to successively close. The stops 9 are preferably so positioned along

the rod 8 as to hold one valve open when the rocking beam 23 is substantially horizontal so that a single ejector serves to extract the air under normal conditions. When 5 air accumulates faster than the single operating ejector can extract it, the pressure within the condenser rises above that maintained in the tank 11 and causes the float 20 to operate the arm 27 to the right sufficiently to open another valve 6, thereby putting another ejector in operation. A further increase in pressure will cause the third 10 valve to be opened. While three ejectors are shown herein for the purpose of illustration, it will be understood that any number of ejectors may be employed.

It is essential to maintain the temperature of the condensate within the tanks 10 and 11 substantially the same as the temperature of the condensate within the condenser 1; therefore a conduit 31 is provided which connects the interior of the tank 11 with the offtake passage 12 and a slight restriction or obstruction 33 is placed in the 25 condensate offtake passage between the points of communication of the pipes 12 and 31, and between the condenser and the withdrawal pump 32. This will promote a flow of condensate through the tanks 10 and 11.

While I have described and illustrated but one embodiment of my invention, it will be apparent to those skilled in the art that various changes, modifications, additions 35 and omissions may be made in the apparatus described and illustrated without departing from the spirit and scope of the invention, as set forth by the appended claims.

What I claim is:

40 1. Condensing apparatus comprising in combination a condenser, means for extracting air from the condenser, and means for controlling the air extracting means, responsive to variations in excess of pressure within the condenser over the vapor pressure of the condensate.

2. Condensing apparatus comprising in combination a condenser, means for extracting air from the condenser, and means for 50 regulating the capacity of the extracting means in response to variations in the absolute pressure of air content of the fluids within the condenser.

3. Condensing apparatus comprising in combination a condenser, means for withdrawing air from the condenser, pressure actuated means for regulating the capacity of the air withdrawing means in response to variations in the mass of the air content 55 of the fluids within the condenser.

4. Condensing apparatus comprising in combination a condenser, means for pumping air from the condenser, means for regulating the capacity of the air pumping 60 means responsive to variations in the pres-

sure difference between the pressure within the condenser and the vapor pressure of the condensate within the condenser.

5. Condensing apparatus comprising a condenser, means for withdrawing air from the condenser, and means for controlling the withdrawing means, in combination with means for actuating the controlling means including a member actuated by condensate subjected to pressure within the condenser 70 and a member actuated by condensate subjected to the vapor pressure of the condensate. 75

6. Condensing apparatus comprising a condenser, means for withdrawing air from the condenser, and means for controlling the withdrawing means including bodies of condensate, one of which is subjected to the pressure within the condenser, and the other of which is subjected to the vapor pressure 80 only of the condensate.

7. Condensing apparatus comprising a condenser, means for pumping air from the condenser, and means for controlling the pumping means including bodies of condensate, one of which is subjected to the pressure within the condenser, and the other of which is subjected to the vapor pressure of the condensate, and means for maintaining the temperature of the bodies of condensate 90 substantially equal. 95

8. Condensing apparatus comprising a condenser, means for pumping air from the condenser, and means for controlling the pumping means including bodies of condensate, one of which is subjected to the pressure within the condenser, and the other of which is subjected to the vapor pressure of the condensate, and means for maintaining the temperature of the bodies of condensate substantially equal to the temperature of the condensate within the condenser. 100 105

9. Condensing apparatus comprising in combination a condenser, means for extracting air from the condenser, and means for controlling the extracting means responsive to relative variations in the level of the condensate exposed to the pressure within the condenser and the level of a portion thereof exposed to the vapor pressure of the condensate. 110 115

10. Condensing apparatus comprising in combination a condenser, means for extracting air from the condenser, means for subjecting a portion of the condensate to its vapor pressure, and means for controlling the extracting means responsive to relative variations of the level of the said portion of the condensate and the level of the condensate within the condenser. 120 125

11. Condensing apparatus comprising in combination a condenser, means for extracting air from the condenser, means for subjecting a portion of the condensate to its vapor pressure, and means for indicating 130

the air content of the fluid within the condenser, responsive to relative variations of the level of the said portion of the condensate and the level of the condensate within the condenser.

12. Condensing apparatus comprising in combination a condenser, means for extracting air from the condenser, means whereby a portion of the condensate is subjected to the vapor pressure of the condensate and means for controlling the air-extracting means including a means responsive to variations in the level of the said portion of the condensate.

13. Condensing apparatus comprising in combination a condenser, means for extracting air from the condenser, a receptacle communicating with the condenser and receiving condensate therefrom, means for subjecting the condensate in the receptacle to the vapor pressure of the condensate at the temperature thereof, and means for controlling the air-extracting means including a means responsive to variations in the level of the condensate within the receptacle.

14. Condensing apparatus comprising in combination a condenser, means for extracting air from the condenser, a receptacle communicating with the condenser and receiving condensate therefrom, means for subjecting the condensate in the receptacle to the vapor pressure of the condensate at the temperature thereof, and means for controlling the air extracting means including a float responsive to variations in the level of the condensate within the receptacle.

15. Condensing apparatus comprising in combination a condenser, means for extracting air from the condenser, a valve for controlling the extracting means, a receptacle communicating with the condenser and receiving condensate therefrom, means for subjecting the condensate within the receptacle to the vapor pressure of the condensate at the temperature thereof, and means for controlling the said valve including means responsive to variations in the level of the condensate within the receptacle.

16. Condensing apparatus comprising in combination a condenser, means for extracting air from the condenser, a receptacle communicating with the condenser and re-

ceiving condensate therefrom, means for maintaining a pressure within the receptacle dependent upon the temperature of the condensate in the receptacle, and means for controlling the air-extracting means including means responsive to variations in the pressure within the receptacle.

17. Condensing apparatus comprising in combination a condenser, means for extracting air from the condenser, a pair of receptacles communicating with the condenser and receiving condensate therefrom, means for subjecting the condensate in one receptacle to the pressure within the condenser, means for subjecting the condensate within the other receptacle to the vapor pressure of the condensate, and means responsive to relative variations of the level of the water in the receptacles for controlling the air extracting means.

18. Condensing apparatus comprising in combination a condenser, valve controlled means for extracting air from the condenser, a pair of receptacles communicating with the condenser and receiving condensate therefrom, means for subjecting the condensate in one receptacle to the pressure within the condenser, means for subjecting the condensate within the other receptacle to the vapor pressure of the condensate, and float means in each receptacle adapted to actuate the valve responsive to relative variations in the level of the condensate within the receptacles.

19. Condensing apparatus comprising in combination a condenser, means for extracting air from the condenser, a pair of receptacles communicating with the condenser and receiving condensate therefrom, means for subjecting the condensate in one receptacle to the pressure within the condenser, means for subjecting the condensate within the other receptacle to the vapor pressure of the condensate, means responsive to relative variations of the level of the water in the receptacles for controlling the air extracting means, and means for circulating water from the condenser through the receptacles.

In testimony whereof, I have hereunto subscribed my name this 5th day of November, 1918.

RAYMOND N. EHRHART.
